UNITED STATES PATENT OFFICE.

CHARLES WHEELANS, OF TRENTON, NEW JERSEY, ASSIGNOR TO L. WOLFF MANUFACTURING COMPANY, OF CHICAGO, ILLINOIS, A CORPORATION OF ILLINOIS.

URINAL.

1,070,643.

Specification of Letters Patent. Patented Aug. 19, 1913.

Application filed April 22, 1912. Serial No. 692,335.

To all whom it may concern:

Be it known that I, CHARLES WHEELANS, a citizen of the United States, residing in Trenton, in the county of Mercer and State of New Jersey, have invented a new and useful Improvement in Urinals, of which the following is a specification.

This invention relates to improvements in urinals.

10 The objects of the invention are to provide a structure in which the urinal stalls may be arranged in a battery, and the parts so constructed and arranged that no cement joints are employed, which, in the present 15 constructions, are objectionable, since these joints soon become dirty and unsanitary; to arrange the structure so that the same may be easily set up and thereby decrease the cost of installation; to so arrange 20 and interfit all the parts, that when the parts are set in place, they form a self locked structure without the use of bolts or other similar devices; and to so arrange 25 the parts that they will not be dislodged by either the sinking of the building in which the stalls are placed, or by warping of the parts, and thus preventing the formation of unsanitary joints and cracks.

In the drawings forming a part of this 30 specification, Figure 1 is a perspective view showing a portion of a battery of urinal stalls embodying my improvements. Fig. 2 is a plan view of a battery of urinal stalls. Fig. 3 is a horizontal, sectional view, taken 35 on the line 3—3 of Fig. 1. Fig. 4 is a partial, back elevation of the structure shown in Fig. 3. Fig. 5 is a vertical section, taken on the line 5—5 of Fig. 2, and Fig. 6 is a detail view, showing parts of the structure.

40 In the drawings, 10, 10 denote the main or body members of each urinal stall, the same being provided with an integrally formed receptor 11, having an outlet 12. Also formed integrally with the main or 45 body member 10 is a splash rim having the vertical side portions 13 and the upper horizontal top portion 14. Each main or body member 10 has also integrally formed therewith flat sides 15, the same being adapted to 50 lie flat against each other when the stalls are placed adjacent each other. A plurality of horizontally disposed top shield members 16 are provided, each of the shield members being provided with a dovetail tongue 17 at 55 the rear end thereof, the same being adapted

to fit in and be held in position by coöperating dovetail grooves 18 formed half in each of the adjacent sides 15 of the main or body members 10. Each shield 16 at its front end is provided with a recess 19 on the under side thereof, and located in front of the front edges of the sides 15 of the stalls, and in which is adapted to be inserted a lug 20 formed integrally with a pilaster 21 at the upper end thereof. Each of the pilasters 21 is provided on its inner face with a recess 22 in which is adapted to closely fit a pair of the front portions of two adjacent sides 15 of the main or body members 10. Each pilaster is also preferably provided with a 70 separating part or partition 23 of the usual form. The members 10 and the lower ends of the pilasters 21 are set below the floor level A in the usual manner, as indicated more particularly in Figs. 1 and 5. Each 75 of the parts is formed of glazed earthenware and from the foregoing description, it will be seen that no joints are presented to eye, and that the parts are so arranged that when in position, all the members are mutually self locked.

In assembling or setting up the parts, the main or body members 10, 10 are first placed side by side and between each pair of members 10, 10 a shield 16 is placed, the same 80 having its tongue 17 inserted from the rear into the groove 18 formed in the two adjacent sides 15 of the members 10, 10. After the shield 16 has been properly placed in position, a pilaster 21 is put in position by 85 first inserting the lug 20 thereon in the recess 19 of the corresponding shield 16, after which the lower end of the pilaster is pushed inwardly until the front edges of the sides 15 are properly seated in the groove or recess 22 on the inner face of the pilaster. When the battery of stalls is placed against the wall B and the tile flooring laid in the usual manner, it will be obvious that it will 90 be impossible for any of the pilasters to be 95 displaced, or for the shields 16 to be moved either backwardly or forwardly, and furthermore, the members 10, 10 will be prevented from moving away from each other laterally, since the same are securely held in 100 place in the grooves 22 of the pilasters 21.

I have described one form of a structure embodying my improvements, but it will be obvious that various changes and modifications may be made in the details thereof 110

without departing from the spirit of the invention, and all such changes and modifications are contemplated as fairly fall within the scope of the claims appended hereto.

I claim:—

1. A battery of urinal stalls comprising, in combination: a plurality of body members, each provided with an integral top, receptor and sides, a plurality of pilasters, each of said pilasters extending from top to bottom of the body members and provided on its inner face with a groove in which are adapted to be seated the front edges of 10 a pair of adjacent sides of two body members, and a plurality of top shields, each of said top shields being provided with an integrally formed tongue thereon at its rear end, and each of the body members being 15 provided with an undercut, half-groove adapted to coöperate with the tongues of the shields and to prevent the latter from being raised out of position after the stalls are in place, the half-groove of one body member being opposite and adjacent the corresponding half-groove of an adjacent body member when the stalls are in position, each of said top shields being provided with an enlarged recess at the front end and on the 20 under side thereof, and each of said pilasters having formed integrally therewith at its upper end a lug, the lugs of the pilasters being adapted to be inserted in the recesses of the shields after the latter are in place,

whereby all the parts are self-locked when 35 the body members, pilasters and shields are in place, substantially as specified.

2. A battery of urinal stalls comprising, in combination: a plurality of body members each provided with an integral top, receptor and sides, and adapted to be placed side by side, each of said members having also an undercut half groove on the tops thereof at the rear side; a plurality of pilasters each having on its inner face a groove 40 within which are adapted to be seated the front edges of a pair of adjacent sides of two body members, each pilaster extending from top to bottom of the body member and having a projection at the top thereof; and 45 a plurality of top shields, each shield having an integrally formed undercut tongue at the rear thereof and an enlarged recess at the front thereof on the under side, whereby the undercut tongues of the shields 50 are adapted to be inserted into said undercut grooves of the body members before the stalls are placed against the wall and said projections on the pilasters are adapted to be inserted in said enlarged recesses of the 55 shields after the latter are in position to thereby form a structure having all of its parts self locked in position, substantially as specified.

CHARLES WHEELANS.
